UNITED STATES PATENT OFFICE.

FRANZ A. FULLER, OF NEWARK, NEW JERSEY.

SAFETY-RAZOR.

1,220,837.

Specification of Letters Patent. Patented Mar. 27, 1917.

Application filed April 17, 1914. Serial No. 832,407.

To all whom it may concern:

Be it known that I, FRANZ A. FULLER, a citizen of the United States, residing in the city of Newark, in the county of Essex and

5 State of New Jersey, have invented certain new and useful Improvements in Safety-Razors, of which the following is a full, clear, and exact description, such as will enable others skilled in the art to which it
10 pertains to make, construct, and use the same, reference being had to the accompanying drawings, and to numerals of reference marked thereon, forming a part of this specification.

15 This invention relates to improvements in safety razors, and the object is to provide a safety razor with a removable razor blade guard, so that when the guard is removed therefrom, the device is adapted for honing
20 and stropping the razor blade.

With this and further objects in view, as will in part hereinafter be set forth, and in part become obvious, the invention comprises certain constructions, combinations
25 and arrangements of parts as hereinafter described and claimed.

In the accompanying drawings,

Figure 1 represents a side elevation of my improved device.

30 Fig. 2 represents a front elevation of the same, with the handle broken away.

Fig. 3 represents a similar view of the device, provided with a modified form of razor blade guard.

35 Fig. 4 represents a sectional under plan view taken on lines $x-x$ of Fig. 1, and looking in the direction indicated by the arrow.

Fig. 5 represents a perspective view of
40 the razor blade guard removed from the device; and

Fig. 6 represents a side elevation of my improved device, partly in section, illustrating the strop in full lines, and showing the

45 manner in which the device is to be used for honing the razor blade, in which case, the blade contacts with the honing or abrading rollers, and the strop in dotted lines, illustrating the manner in which the device
50 is to be used for stropping the razor blade, in which case, the blade engages with the strop.

Similar numerals of reference refer to like parts throughout the specification and
55 drawings.

In the drawings, 1 represents the body or

frame of my improved device, which body may be stamped from sheet metal or the like and afterward bent into the desired shape as shown. Said body or frame comprises two opposite side portions 2 and 3, parallel each to each, and connected by a lower curved central cross-piece or guide 4, to which a handle 5 is secured in any convenient or desired manner. The said side portions 2 and 3 are adapted to lie at the opposite edges of a strop 6 with the cross-piece or guide 4 beneath and the handle 5 depending therefrom in convenient position to slide the device longitudinally of the strop.

In Fig. 6 of the drawings, I have shown the body or frame 1 further provided with a central upper curved cross-piece or guide 7 connected to said side portions 2 and 3 in any convenient or desired manner. These guides 4 and 7 are so arranged with relation to the lower roller 14 and the upper shaft 13 of the device, as to provide sufficient space for the entrance of the end of the strop, and are further so arranged that if the strop is to be inserted in the device when the same is to be used for stropping the blade, the end of the strop, after passing over the roller 8 as illustrated in dotted lines in Fig. 6 of the drawings, will pass between the roller 14 and the guide 4, and then up over the other roller 8, and should it be desired to insert the strop for honing the blade, the end of the strop after passing under the roller 8 is passed between the roller 14 and the guide 7, and then down under the other roller 8, as illustrated in full lines in Fig. 6 of the drawings.

Journaled in the ends of the frame 1, are rollers 8-8, each consisting preferably of stone or any other suitable honing or abrading material, rotatably mounted on a cylindrical rod or shaft 9 fixed at its ends to the respective side portions 2 and 3 of the body or frame 1. These two rotatable honing and stropping rollers 8 are provided with a helical groove 10, or if desired, with a plurality of short helical grooves, and serve as rollers for honing the razor blade when the device is to be used for honing the blade, as illustrated in Fig. 6 of the drawings, and serve as strop carrying or guiding rollers when the device is to be used for stropping the blade, as illustrated in said view of the drawings.

The rollers 8-8 are preferably spaced

apart for approximately the width of the device, and disposed intermediate the width of the device, are upwardly projecting ears 11. Said ears 11 have upper and lower holes 5 forming bearings for the pivoted ends of an upper shaft 13 and a lower roller 14, both extending transversely of the frame 1. The upper shaft 13 and the lower roller 14 are connected by means of pinions or gears 12 and 15, shown in dotted lines, so that drawing the device along the strop will tend to turn the said shaft 13, and when the direction of sliding the device is reversed, the shaft 13 will be turned over according to the 10 principles already well understood in the art.

The shaft 13 carries the blade holder 17, which holder may consist of a piece of sheet metal wrapped around the shaft 13 and secured thereto in any convenient or desired manner, so as to provide resilient clamping jaws 18 and 19 to receive the razor blade 20 between themselves, as has been common in general heretofore.

25 The razor blade as shown, is preferably made of sheet steel, provided with a substantially plane portion along one longitudinal edge, and having a longitudinal cutting edge on the side opposite said portion, the blade 30 intermediate said portion and said cutting edge, comprising a uniformly concave portion on which the cutting edge is formed, and lying entirely on one side of the central plane of the said first mentioned portion, 35 and having an offset portion connecting said concave portion with said first mentioned portion. The ear or lug 11 in the frame 1 in its upper side, is provided with a recess 21, which recess when the blade holder is in 40 a vertical position, will correspond with the space between the resilient clamping jaws 18 and 19 of the blade holder, so as to provide a ready means for the insertion and removal of the blade 20 from the holder 17.

45 The razor blade guard 22 is preferably made of sheet metal, stamped and formed from a single blank (see Fig. 5). To an extension formed on the under side thereof, is secured in any convenient manner, a locking lever 23, pivoted at 24, the free end 25 of said locking lever being so formed as to engage with the free end 26 of a spring-tongue 27, which is secured to the under side of the cross-piece 4 of the frame 1 by 50 means of screws 28, thus providing means by which the guard 22 is securely clamped to the frame 1.

55 29 represent offset portions or guides, designed to have sliding engagement with the 60 opposite side portions 2 and 3 of the body or frame 1. The blade guard 22 is constructed to grip the blade 20 at the front corners, the sharpened edge of the blade resting upon the curved portion of the 65 guard, which is provided with the usual

perforations 30, said curved portion being sufficiently in advance of the edge of the blade to afford the necessary protection against accidental cutting.

The upper and outer ends of the guard 70 have upwardly extending stops 31 for engagement with the corners of the cutting edge of the blade 20 to prevent said cutting edge from projecting too far beyond the guard 22, to at all times maintain the cutting edge of the razor in the proper and adjusted position, relative to the guard teeth.

32 represent pressed-out portions or stops on the under side of the guard plate to limit the movement of the pivoted locking lever 23.

In Fig. 3 of the drawings, I have shown a modified form of guard, in which the upper and front portions of the same, in which the perforations 30 are located, is cut away 85 in such a manner as to expose the roller 8, which in a measure serves as a guard.

The operation of the device is as follows:

When the device is to be used for shaving, the structure illustrated in Fig. 1 is to 90 be used, and when the device is to be used for honing purposes, the guard 22 is removed, and the strop, shown in full lines, is then passed under one of the rollers 8, at one end of the frame 1 and between the lower 95 roller 14 and the guide 7, and then through and under the other roller 8 of the device, as clearly indicated in Fig. 6 of the drawings. The attached end of the strop, (not shown) is hooked over any suitable support, 100 while its opposite end, (likewise not shown) is held in one hand. The other hand grasps the handle 5 of the device, and reciprocates said device back and forth along the strop, thereby permitting the blade to be engaged 105 with the honing or abrading rollers 8-8. When it is desired to use the device for stropping the razor, it is only necessary to pass the strop over one of the rollers 8 at one end of the frame 1, and between the 110 lower roller 14 and the guide 4, and then out through and over the other end roller 8 of the device, as clearly indicated in dotted lines in Fig. 6, then by reciprocating the device along the strop as above described, the 115 blade will be brought into contact with the strop instead of with the abrading rollers 8-8.

I am aware that changes may be made in the several arrangements of the various 120 parts, as well as in the details of construction thereof, without departing from the scope of my present invention, hence I do not wish to be limited to the arrangements and combinations of parts as herein shown 125 and described, as obvious modifications will suggest themselves to those skilled in the art.

I claim:

1. A safety razor comprising a frame, said frame comprising two opposite side por- 130

- tions parallel each to each, and connected by a lower central cross-piece, a handle secured to said central cross-piece, a blade holder pivoted on said frame directly above 5 said central cross-piece, a razor blade guard detachably secured to the two opposite side portions of said frame, a spring tongue secured to the under side of the central cross-piece of the frame and a locking lever secured to the under side of said guard, the 10 free end of said locking lever engaging with a spring tongue for positively adjusting the blade relative to the guard.
2. A safety razor comprising a frame, 15 said frame comprising two opposite side portions parallel each to each, and connected by a lower central cross-piece, a handle secured to said central cross-piece, a blade holder pivoted on said frame directly above said 20 central cross-piece, a razor blade guard detachably secured to the two opposite side portions of said frame, means carried by said guard for positively adjusting the blade relative to the guard, said razor blade guard 25 being further provided with guides designed to have sliding engagement with the opposite side portions of the frame for detachably securing the guard to said frame, a spring tongue secured to the under side of 30 the central cross-piece of the said frame and a locking lever secured to the under side of said guard for positively adjusting the blade relative to the guard.
3. A safety razor comprising a frame, 35 adapted to slide longitudinally of a strop, said frame comprising two opposite side portions parallel each to each, a blade holder pivoted on said frame with a line of pivoting transverse to the strop, a roller pivoted 40 low said blade holder on the frame for transmitting rotary movement to said blade holder, guides arranged upon said frame and located above and below said roller for guiding the strop, a razor blade guard detachably secured to the two opposite side 45 portions of said frame, means carried by said guard for positively adjusting the blade relative to the guard, said razor blade guard being further provided with guides designed to have sliding engagement with the opposite 50 side portions of the frame for detachably securing the guard to said frame, a spring tongue secured to the under side of the central cross-piece of the said frame and a locking lever secured to the under side of 55 said guard for positively adjusting the blade relative to the guard.
4. A safety razor comprising a frame, said frame comprising two opposite side portions parallel each to each, and connected by a 60 lower central cross-piece, a handle secured to said central cross-piece, a blade holder pivoted on said frame directly above said central cross-piece, said frame being further provided with a recess in one of the side portions thereof for the insertion and removal of the blade from the blade holder, a razor blade guard detachably secured to the two opposite side portions of said frame, a spring tongue secured to the under side of the central cross-piece of the frame and a locking lever secured to the under side of said guard, the free end of said locking lever engaging with a spring tongue for positively adjusting 65 the blade relative to the guard. 70
